UNITED STATES PATENT OFFICE.

HERMANN MERKEL, OF ST. LOUIS, MISSOURI.

DESIGN FOR A HYDROCARBON-BURNER.

SPECIFICATION forming part of Design No. 33,377, dated October 16, 1900.

Application filed July 30, 1900. Serial No. 25,357. Term of patent 14 years.

To all whom it may concern:

Be it known that I, HERMANN MERKEL, a citizen of the United States, residing at St. Louis, in the State of Missouri, have invented and produced a new and original Design for Hydrocarbon-Burners, of which the following is a specification.

Figure I is a side elevation of a hydrocarbon-burner embodying my design. Fig. II is a top plan view.

This, as shown in the drawings, the leading or material feature in my design consists of the valve-casing 1, the arms 2 and 3, extending upwardly from opposite sides of the upper end of the valve-casing, the nipples 4 and 5, extending horizontally from the ends

of the arms 2 and 3, and the mixing-chamber 6, extending upwardly from the inner ends of the nipples 4 and 5. The rectangular recesses 7 are formed in the outer surface of the upper end of the mixing-chamber, and the gas-openings 8 lead from the upper end of the mixing-chamber down into the recesses 7. The gallery-supporting bead 9 is located at a point near the center of the mixing-chamber. 25

I claim—

The design for a hydrocarbon-burner substantially as herein shown and described.

HERMANN MERKEL.
